1 Claim

ABSTRACT OF THE DISCLOSURE

A journal lubricating apparatus featuring a pump mounted on an exterior wall of the journal box, an oil suction tube extended into said box from the pump into an oil well disposed at the lower portion of the box, a pump rod extended into the box from the pump adapted to engage a projection on the journal, an elongated, perforated spray tube extended into the box from the pump disposed parallel to the journal to spray a fine mist of oil evenly over the journal surface and a journal within the box having an offset projection extended from its surface, said projection being adapted to engage a pump rod to actuate the pump upon revolution of the journal.

This invention relates to the improvement of the methods now in use of lubricating journals of railway boxcars in transit. Accordingly it is the object of said invention to provide proper oil lubrication to said journal while boxcar is in motion in an improved inexpensive technique with fewer moving parts.

Said invention dispenses with waste lubrication, pads; and or felt material that causes trouble enroute by becoming dislodged and the lubricating principle of said pads lost causing hot-box conditions. Said invention contains fewer moving parts and will become apparent from the detailed description in conjunction with the drawing of said invention.

In general terms said invention may be stated as a journal lubricating apparatus, comprising a journal box, a fuel pump anchored on the outside surface of a wall of the box, an oil suction tube extended from the pump into an oil well disposed at the lower portion of the box, a pump rod extended into the box from the pump adapted to engage a projection on the journal, an elongated, perforated spray tube extended into the box from the pump disposed parallel to the journal to spray a fine mist of oil evenly over the journal surface and a journal within the box having an offset projection extended from its surface, said projection being adapted to engage a pump rod to actuate the pump upon revolution of the journal.

2

FIG. 1 is a transverse sectional view of the journal box showing lubricator mounted therein.

FIG. 2 is a longitudinal sectional view showing lubricator mounted therein.

Referring now to the lubricator of which the invention pertains, said lubricator includes a common fuel pump 1 anchored on the outside surface of a wall of said journal box 7.

An oil suction tube 2 extends from the pump 1 into an oil well 8 disposed at the lower portion of said journal box 7.

A pump rod 3 extends into said journal box 7 from said pump 1 adapted to engage a projection 4 on the journal 5 within said box.

15 An elongated perforated spray tube 6 extends into the journal box 7 from said pump 1 disposed parallel to said journal 5 to spray a fine mist of oil evenly over the surface on the underside of the journal 5 within said box, said journal 5 having an offset projection 4 on its rim; said projection 4 being adapted to engage pump rod 3 to actuate fuel pump 1 upon revolution of said journal 5.

Having described the invention or discovery, the construction, the operation and use, obvious to those skilled in the art set forth in the appended claim.

25 I claim:

1. A journal lubricating apparatus, comprising a journal box, a fuel pump anchored on the outside surface of a wall of the box, an oil suction tube extended from the pump into an oil well disposed at the lower portion of the box, a pump rod extended into the box from the pump adapted to engage a projection on the journal, an elongated, perforated spray tube extended into the box from the pump disposed parallel to the journal to spray a fine mist of oil evenly over the journal surface and a journal within the box having an offset projection extended from its surface, said projection being adapted to engage the pump rod to actuate the pump upon revolution of the journal.
